Int. Cl. D24—03

U.S. Cl. D24—1

FIG. 1

FIG. 2

FIG. 3

FIG. 4

FIG. 1 is a perspective view of a control cabinet for dental handpieces, showing our new design;

FIG. 2 is a front elevational view of the cabinet;

FIG. 3 is a top plan view;

FIG. 4 is a side elevational view, the opposite side being substantially identical but in reverse form.

The parts shown in broken lines are for illustrative purposes only. The rear of the control cabinet is substantially plain except for the two projecting coupling elements shown in FIGS. 3 and 4.

We claim:

The ornamental design for a control cabinet for dental handpieces, substantially as shown and described.
